(57) **CLAIM**

The ornamental design for ready-to-assemble article of furniture, as shown and described.

DESCRIPTION

FIG. 1 is a perspective view of one embodiment of a ready-to assemble article of furniture according to the present invention, configured as an upright shelving unit.

FIG. 2 is a front elevational view of the embodiment shown in FIG. 1.

FIG. 3 is a back elevational view of the embodiment shown in FIG. 1.

FIG. 4 is a side elevational view of the embodiment shown in FIG. 1, with the opposite side view being a mirror image. FIG. 5 is a bottom elevational view of the embodiment shown in FIG. 1.

FIG. 6 is a top elevational view of the embodiment shown in FIG. 1.

FIG. 7 is a perspective view of another embodiment of a ready-to assemble article of furniture according to the present invention, configured as an upright shelving unit.

FIG. 8 is a front elevational view of the embodiment shown in FIG. 7.

FIG. 9 is a back elevational view of the embodiment shown in FIG. 7.

FIG. 10 is a side elevational view of the embodiment shown in FIG. 7, with the opposite side view being a mirror image.

FIG. 11 is a bottom elevational view of the embodiment shown in FIG. 7.

FIG. 12 is a top elevational view of the embodiment shown in FIG. 7.

FIG. 13 is a perspective view of a further embodiment of a ready-to assemble article of furniture according to the present invention, configured as a horizontal shelving unit.

FIG. 14 is a front elevational view of the embodiment shown in FIG. 13.

FIG. 15 is a back elevational view of the embodiment shown in FIG. 13.

FIG. 16 is a side elevational view of the embodiment shown in FIG. 13, with the opposite side view being a mirror image.

FIG. 17 is a bottom elevational view of the embodiment shown in FIG. 13; and,

FIG. 18 is a top elevational view of the embodiment shown in FIG. 13.
